UNITED STATES PATENT OFFICE

153,901

DESIGN FOR A TOASTER

Jean O. Reinecke, Oak Park, Ill., assignor to McGraw Electric Company, Elgin, Ill., a corporation of Delaware

Application July 9, 1946, Serial No. 131,408

Term of patent 14 years

(Cl. D81—10)

To all whom it may concern:

Be it known that I, Jean O. Reinecke, a citizen of the United States, residing in Oak Park, county of Cook, and State of Illinois, have invented a new, original, and ornamental Design for a Toaster, of which the following is a specification, reference being had to the accompanying drawings, forming a part thereof, in which

Fig. 1 is a view in side elevation of a toaster showing my new design;

Fig. 2 is a top plan view thereof;

Fig. 3 is a view of one end; and

Fig. 4 is a perspective view thereof and showing the same end as Fig. 3.

I claim:

The ornamental design for a toaster, substantially as shown.

JEAN O. REINECKE.
